United States Patent Office

Des. 185,645
Patented July 7, 1959

185,645

COMBINED DEBURRING AND METAL POLISHING MACHINE

Haskell J. Miller, Glendale, Calif.

Application May 22, 1957, Serial No. 46,294

Term of patent 14 years

(Cl. D37—1)

FIG. 1.

FIG. 2.

FIG. 3.

FIG. 4.

FIG. 5.

Figure 1 is a front elevational view of a combined deburring and metal polishing machine embodying my new design;

Figure 2 is a perspective view taken from the left of Figure 1;

Figure 3 is a top plan view of the machine;

Figure 4 is a rear elevational view of the machine; and

Figure 5 is an end elevational view as taken from the right-hand end of the machine as viewed in Figure 1.

I claim:

The ornamental design for a combined deburring and metal polishing machine, as shown.
